UNITED STATES PATENT OFFICE.

CHESTER McNEIL, OF CHICAGO, ILLINOIS, ASSIGNOR TO UNION SPECIAL MACHINE COMPANY, OF CHICAGO, ILLINOIS, A CORPORATION OF ILLINOIS.

METHOD OF MAKING BELT-LOOPS.

Specification of Letters Patent.

Patented May 2, 1916.

1,181,604.

Application filed June 13, 1914. Serial No. 844,933.

To all whom it may concern:

Be it known that I, CHESTER McNEIL, a citizen of the United States, residing at Chicago, in the county of Cook, State of Illinois, have invented certain new and useful Improvements in Methods of Making Belt-Loops, of which the following is a description, reference being had to the accompanying drawing and to the figures of reference marked thereon.

10 My invention relates to methods of making straps, and more especially straps which are utilized as belt loops for trousers.

15 In its application to belt loops the object is to utilize scraps of material of which the garment is made and to form the same by folding in the side portions along a longitudinal line so that they substantially abut at the center of the body fabric, the side portions being secured together and to the body 20 portion by stitches which do not show on the face of the completed article. Cross threads also may be provided as part of the stitches which secure the stitches and also bind the 25 raw edges of the material.

26 The invention therefore primarily consists in folding the side portions of a strip of material so that they abut one another in the center of the fabric, and then passing 30 rows of loops through one of the folded side portions into the central body portion and through the other folded side portion and securing said loops of thread. Secondly, it consists in securing said loops of thread by 35 cross threads which hold the latter and also serve to cover the raw edges of the folded in portions.

36 The invention is illustrated in the accompanying drawings, in which,

40 Figure 1 is a cross section of a strap made in accordance with my method showing the strap bent to receive the stitches. Fig. 2 is a similar view with the strap in normal condition. Figs. 3 and 4 are respectively enlarged bottom and top plan views. Fig. 5 is a view similar to Fig. 2 with the cross stitching omitted. Fig. 6 is a view similar to figure 5 showing the edges folded. Fig. 7 is a plan view of the strap shown in Fig. 5.

45 In forming my strap the edges of the narrow strip of material are first trimmed, if of irregular shape or frayed, and the side portions are folded to bring such folded in portions together at the back of the strap and 50 along the center line thereof.

As shown in Fig. 1, the strap has side portions 2 and 3 folded back upon the body portion of the strap and said side portions 2 and 3 have their edges abutted or meeting as at 4.

55 If a belt loop for trousers is to be made, I take scraps of the material of which the trousers are made, and cut them into the desired width and fold them as above stated.

60 A series of loops 5 is passed into one of the folded portions 2 or 3 at an inclination to the face of said portion and passed through the body of the strap entering and emerging on the rear face thereof adjacent to the folded in portions. Said loops are entirely imbedded in the body portion so that 65 they do not show on the face of the strip (see Fig. 4).

66 In passing the loops 5 through the folded strip, I bend the latter as shown in Fig. 1 and with a curved or straight needle the 70 loops 5 may be passed through the folded in portions and the body fabric in the manner above described.

75 The thread 6 as herein shown is formed into loops which are passed through loop 5 in the thread 5 and carried across the meeting edges of the folded in portions to the point where the loop enters the folded in portion where it is united with the base of said loop. 80 Instead of using a thread which is in loop form and arranged as herein shown, for locking with the loops embedded in the strip, it is evident that any other style of cross stitching may be used, the essential feature of the 85 article made according to my invention being that certain threads are passed through the folded in portion and the body of the strip, while other threads are laid across the meeting edges. These cross threads serve to 90 cover the meeting edges and form a neatly finished belt loop. The embedded threads not only connect the folded in edges and 95 serve as a means for tying the cross threads but they also tie the folded in portions to 100 the body portion of the strip, so that a flat belt loop of substantially unitary structure is formed.

105 In Fig. 5 the cross stitching is omitted, as well as in Fig. 6; in the latter figure the 9 portions 2 and 3 being again folded as at 9 and 10 so as to cause the meeting edges to be folded edges, thus binding the raw edges 110 between the portions 2, 3 and the body portion of the strap.

Having thus described my invention, what I claim as new and desire to secure by Letters Patent is:

- 5 1. The herein described method of forming straps or belt loops which consists in initially folding the side portions longitudinally back against the central or body portions with their edges substantially abutting at the central line of the body portion and
- 10 then passing loops of threads through one of said folded side portions, entering the central body portion and passing through the other folded side portion, as and for the purpose set forth.
- 15 2. The herein described method of forming straps or belt loops which consists in initially folding the side portions longitudinally back against the central or body por-

tion with their edges substantially abutting at the central line of the body portion and 20 then passing loops of thread through one of said folded side portions, entering the central body portion and passing through the other folded side portion and then securing the loops by cross threads which extend 25 across between the edges of the folded side portions and overlie and cover the abutting edges of the folded in side portions, as and for the purpose set forth.

In testimony whereof I affix my signature, 30 in the presence of two witnesses.

CHESTER McNEIL.
